UNITED STATES PATENT OFFICE.

ARTHUR DEMONT BUSH, OF OLIVET, MICHIGAN.

DISH-WASHER.

1,215,107.

Specification of Letters Patent.

Patented Feb. 6, 1917.

Application filed December 30, 1915. Serial No. 89,385.

To all whom it may concern:

Be it known that I, ARTHUR D. BUSH, a citizen of the United States, and a resident of Olivet, in the county of Eaton and State 5 of Michigan, have invented a new and Improved Dish-Washer, of which the following is a full, clear, and exact description.

My invention relates to an automatic dish-washing machine. The object thereof is to 10 provide a simple, sanitary and inexpensive machine which will rinse dishes to be washed, wash them with a boiling, cleansing solution, rinse them to remove the cleansing solution, and deliver the so-cleaned dishes.

15 With the above and other objects in view, the nature of which will more fully appear as the description proceeds, the invention consists in the novel construction, combination and arrangement of parts as herein 20 fully described, illustrated and claimed. In the accompanying drawings, forming part of the application, similar characters of reference indicate corresponding parts in all the views.

25 Figure 1 is a longitudinal section of a preferred embodiment of my dish-washing machine;

Fig. 2 is a fragmentary, horizontal section on line 2—2, Fig. 1;

30 Fig. 3 is a vertical cross section on line 3—3, Fig. 1;

Fig. 4 is a similar section on line 4—4, Fig. 1;

35 Fig. 5 is a vertical cross section on line 5—5, Fig. 1;

Fig. 6 is an enlarged, fragmentary sectional view through the tank for the cleansing solution and showing the flashing tube in elevation; and

40 Fig. 7 is a horizontal cross section through the flashing tube on line 7—7, Fig. 6.

Referring to the drawings, 8 is a casing having transverse partitions 9 spaced from the top of the casing and sub-dividing the 45 lower part of the casing into successive compartments 10, 11, 12, 13 and 14. The compartment 10 receives a water motor 15 to be actuated by the flow of water which is utilized in the machine for cleansing purposes.

50 Other motive-power means can be used if so desired, but this is a preferable form. The casing 8 at the front and rear ends thereof

is provided with extensions 16 forming tables at the level of the partitions 9. Each of said tables is preferably provided with a 55 surface formed of rollers 17 to facilitate the movement of the dishes placed upon the surface. The feeding table 16 preferably slopes toward the casing so as to facilitate the movement of the dishes placed upon the surface into the casing, while the delivery table slopes from the casing to facilitate the movement of the dishes coming out of the casing.

Cooperating with the surface 17 of the 65 tables is a conveyer 18 extending between said tables over the compartments in the casing. Said conveyer is preferably formed of a plurality of rollers 19 rotatably mounted in a frame 20 extending over the tables 70 16. Each of the rollers is provided with a gear 21 in mesh with a screw 22 extending longitudinally of the conveyer and adapted to be driven from the motor 15 through the medium of any suitable transmission 23 provided therebetween. The rollers 19 have the central part thereof removed to offer a greater clearance.

In register with the clearance above the compartment 10 is a sprinkler 24 leading to 80 a main supply 25. The connection between the sprinkler and the main is beyond the motor 15. In addition to the main sprinkler 24 sprinklers 26 branch out from the sprinkler 24, the said sprinklers 26 being located 85 at suitable intervals so as to register with the spaces between the rollers 19. These sprinklers will rinse the dishes carried by the conveyer with cold water. The compartment 11 has in the clearance formed by 90 the rollers 19 a sprinkler 27 similar to the sprinkler 24 and having branches 28 therefrom similar to the branches 26. The sprinkler 27 is also connected to the main but through the medium of a heating coil 29 located in the chamber 11 above a heat-supplying device 30, which is preferably a gas burner. The sprinklers 27 and 28 will supply hot water for rinsing the dishes moving above the compartment 11.

100 The compartments 10 and 11 are provided with a common roof 31 located below the sprinklers and converging toward the partition between the compartments. A drain

32 connects the lowest part of the roof with a liquid outlet 33 of the casing provided within the compartment 13. The roof 31 forms a basin or receptacle for collecting the water supplied through the sprinklers.

5 A tank 34 is provided in the compartment 12 above a gas burner 35 within the compartment, the bottom of the tank forming a depressed roof for the compartment 12, and the tank forming the collecting basin for the liquid supplied above said compartment. Flashing tubes 36 are interposed between the burner and the tank 34. Liquid is supplied to said flashing tubes 36 by a conduit 15 37 extending from the bottom of the tank 34, said flashing tubes having ejecting ends 38 passing through the bottom of the tank and extending substantially to the upper level thereof so as to be normally about half 20 an inch below the liquid level in the tank. The portions of the flashing tubes above the burner have their heating area increased without materially increasing their cross section, thereby exposing a large surface of 25 the tube 36 to the action of heat coming from the burner and thereby generating steam rapidly in the enlarged portion of the tubes, the generated steam causing a violent eruption of the cleansing solution from the 30 tank 34. The cleansing solution within the tank may be of any suitable composition according to the character of the dishes to be cleaned. The heat supplied to the flashing tubes will also supply heat to the tank 34, thereby maintaining the cleansing solution 35 at a high temperature.

The compartment 13 is in communication with the compartments 11 and 12 to receive the gases of combustion therefrom and direct 40 the same out from the casing through a conduit 39. If desired, special flues may be provided from the compartments 11 and 12 to the compartment 13. A roof 40 is provided at the top of said compartments 45 which slopes downwardly and toward the tank 34 to convey thereto any liquid that may fall upon said roof. Located above said roof 40 is a tube 41 adapted to supply a single spray for washing off the major portion 50 of the cleansing substance that remains on the dishes. This liquid will be carried off by the roof 40 into the tank 34 for which an overflow 42 is provided leading to the outlet 33. The tube 41 forms an extension 55 of a sprinkler 43 located above the compartment 14 and connected to the main 25 by a heating coil 44 which is heated by a gas burner 45, both the coil and burner being provided within the compartment 14. A roof 60 46 is provided over the compartment 14 below the sprinkler 43, the roof sloping toward the partition 9 whereat a drain 47 is provided connecting the roof and the outlet 33. The sprinkler 43 is adapted to deliver 65 boiling water so as to easily wash the

dishes passing thereabove. This latter washing cleanses the dishes thoroughly from whatever cleansing solution may remain thereupon, and the dishes are delivered thoroughly clean to the adjacent table 16.

70 A section 48 of the compartment 8 which surrounds the conveyer is preferably narrower than the casing, and is detachable. Its width is preferably slightly less than that of the conveyer. It is made detachable from the main part of the casing 8 to facilitate its cleansing and also to facilitate the inspection of the most active part of the machine. Preferably one side of the casing section 48 is rendered transparent, as shown 75 at 49, to facilitate the inspection of the operation of the machine and wherethrough the cleansing of the dishes by the machine may be observed.

80 While I have described the principle of 85 operation, together with the device which I now consider to be the best embodiment thereof, I desire to have it understood that the device shown is merely illustrative and that such changes may be made as are within the scope of the appended claims.

90 I claim:

1. In a dish washing machine, a casing, a conveyer for conveying the dishes to be cleaned through the casing, a fluid tank below said conveyer having a constant level of 95 cleaning fluid therein, means for spraying rinsing fluid upwardly in the casing and also located below the conveyer, steam discharge pipes leading into the tank and having their ends terminating below the level of the fluid therein, whereby to spray the fluid upwardly with the steam, and steam generating means with which said steam discharge pipes are connected.

100 2. In a dish washing machine, a casing, a conveyer for conveying the dishes to be cleaned through the casing, a fluid tank below said conveyer having a constant level of 105 cleaning fluid therein, means for spraying rinsing fluid upwardly in the casing and located below the conveyer, steam discharge pipes leading into the tank and having their ends terminating below the level of the fluid therein, whereby to spray the fluid upwardly with the steam, and steam generating means with which said steam discharge pipes are connected, said fluid tank having a fluid supply leading to the steam generating means whereby both the steam from the 110 discharge pipes and the spray induced thereby will be of the same nature.

115 3. In a dish washing machine, a casing, a conveyer for conveying the dishes to be cleaned through the casing, means below the 120 conveyer for spraying a cleaning fluid upwardly within the casing, steam and water spray pipes at opposite sides of said fluid spraying means, heating coils with which 125 said spray pipes communicate, a supply 130

common to the said coils, and a heating burner beneath each of said coils, said casting having covered compartments at opposite sides of the said fluid spraying means, for housing said coils and said burners, provided with outlets for the products of combustion from the burners.

In testimony whereof I have signed my name to this specification in the presence of two subscribing witnesses.

ARTHUR DERMONT BUSH.
